HARRY SWINGLEHURST, OF ORANGE, NEW JERSEY, ASSIGNOR TO SCOTT & WILLIAMS,
INCORPORATED, OF NEW YORK, N. Y., A CORPORATION OF MASSACHUSETTS

NEEDLE DIAL FOR KNITTING MACHINES

Application filed February 17, 1932. Serial No. 593,576.

This invention relates to knitting machines and more particularly to the needle dials therefor and it is an object of this invention to provide a needle dial of improved construction in which needle slots or grooves are arranged in groups of parallel grooves having finished parallel side walls. It is also an object of this invention to provide a needle dial of the type described in which the needle grooves are formed by walls inserted in slots in the dial. It is also an object of this invention to provide a needle dial of the type described which will be of a construction giving a maximum service and permitting of ready repair.

In the drawing:

Fig. 1 is a top plan view showing a segment of a needle dial constructed in accordance with this invention;

Fig. 2 is a vertical section taken as on the line 2—2 of Fig. 1; and

Fig. 3 is a diagrammatic view showing an arrangement of the needles in the cylinder and dial for use in connection with a dial arranged as in Fig. 1.

The needle arrangement shown in Fig. 3 is one used in connection with 2 x 2 Swiss rib knitting and is shown to illustrate an arrangement of dial needles N' and cylinder needles N suitable for use with a needle dial arranged as shown in Fig. 1. It is to be understood that the dial may be arranged for other arrangements of needles.

A dial constructed in accordance with this invention comprises a circular plate or disk 1 having the usual central bore (not shown) by which the plate is mounted on the usual dial shaft or post. Adjacent its edge the plate 1 is formed with an annular rib 3 which projects upwardly from the flat upper surface 5 of the plate. The upper surface 5 ends intermediate the periphery and the center of the plate and is connected by a vertical surface 7 to an upper surface 9 at a lower level than the surface 5. At regular intervals around the plate 1 groups of parallel slots of different widths 11 are cut in the surface 5 of the plate, these slots being formed parallel to the radius which is located substantially centrally of the group and extend-

ing from the surface 7 outwardly to points adjacent the rib 3. In the slots 11 are inserted the walls 14a, 14b, 14c which project above the surface 5 of the plate and are of such dimensions as to form slots or grooves 15 therebetween of the desired width and spacing for the needle arrangement selected. As shown in the drawing, three parallel slots 11 are formed in each group and the walls or blocks 14a, 14b and 14c inserted in these slots 15 correspond in width thereto. The walls or blocks of each group are angularly disposed with respect to the walls or blocks of adjacent groups.

As shown in Fig. 1, the intermediate wall 14b of each group is the thickest and is of the proper thickness to give the desired spacing between the needles. The last block 14c of the group is of greater thickness than the leading block 14a of the group, although neither block is of the full width of the needle spacing, as the block 14c is subjected to the lateral pressure of the needle in the adjacent slot resulting from the action of the cams on the needle while the wall 14a is not subjected to such pressure and may be made lighter or thinner. Wall 14b is also subjected to the pressure of the needle but when made of proper thickness for the needle spacing it is sufficiently strong to withstand the needle pressure. Making the end slots 11 of each group narrower than the intermediate slot permit of retaining in the limited space available between end slots of adjacent groups a portion of the dial body 1 which extends to the inner edge of the upper surface 5 separating the inner ends of the slots and which is of sufficient thickness to resist being laid over or broken off by the cutting tool in the cutting of the slots. This portion of the dial body is also of sufficient strength to provide adequate support for the adjacent wall 14c against the pressure of the needle. With the slots extending to the inner edge of the surface 5 and of uniform width throughout, it is possible to have each wall of uniform width for its full length and of sufficient strength to withstand the usual needle pressure without having their inner ends abutting or cut away to avoid

- interference due to their convergence. The surface 5 may be hardened and ground true after the slots 11 for the walls are cut therein and the walls 14a, 14b and 14c may be hardened and ground before insertion in the slots 11. In this way a needle slot having a hardened and true wearing surface is provided for the needle. Continuations 15a of the slots 15 are formed in the annular rib 5 of the slots 3 so as to permit the passage of the needles and form a guide for the ends thereof.
- What is claimed is:—
1. A dial having groups of spaced parallel slots therein and walls inserted in said slots having the opposing faces of adjacent walls parallel.
  2. A dial having groups of inserted walls, the walls of each group being parallel and angularly disposed with respect to the walls 15 of adjacent groups.
  3. A needle dial having groups of inserted walls, the walls of each group forming parallel needle grooves angularly disposed with respect to the grooves of adjacent groups.
  4. A needle dial having groups of inserted parallel walls, the walls of each group having parallel opposed faces forming needle grooves.
  5. A dial having groups of inserted parallel walls of different thickness, the walls of each group having parallel opposed faces forming needle grooves.
  6. A dial for knitting machines having groups of inserted parallel walls of different thickness, the walls of each group having parallel opposed faces forming needle grooves, angularly disposed with respect to the needle grooves of adjacent groups.
  7. A dial having groups of inserted parallel walls of different thickness having parallel opposed faces forming needle grooves, the walls of adjacent groups being angularly disposed.
  8. A dial for knitting machines having groups of parallel slots therein, the slots of adjacent groups being angularly disposed and walls inserted in said slots, the walls in each group of slots having parallel opposed faces forming needle grooves angularly disposed to the needle grooves of adjacent groups.
  9. A dial having groups of spaced parallel slots the slots of each group being parallel to the radius through the center of said group and walls of different thicknesses mounted in said slots, the walls in each group of slots having parallel opposed faces forming needle grooves.
  10. A dial having groups of spaced parallel slots with the slots of each group parallel to the radius through the center of said group and walls of different thicknesses mounted in said slots, the walls in each group 65 of slots having parallel opposed faces form-

ing needle grooves angularly disposed to the needle grooves formed by adjacent groups.

11. A dial having groups of spaced parallel slots, the slots of adjacent groups being angularly disposed, and walls of different 70 thickness mounted in said slots, the walls in each group of slots having parallel opposed faces forming needle grooves with the grooves of adjacent groups angularly disposed.

12. A dial for knitting machines having groups of spaced parallel slots, the slots of adjacent groups being angularly disposed, rectangular walls of different thicknesses 80 mounted in said slots with the walls in each group of slots parallel and angularly disposed to the walls in adjacent groups of slots and the walls in each group of slots forming spaced parallel grooves angularly disposed to the grooves formed by the walls in adjacent 85 groups of slots.

13. A dial having groups of inserted parallel walls of different thickness, the walls of each group having parallel opposed faces forming grooves for a plurality of needles, the leading wall being thinner than the wall forming the opposed face.

14. A dial for knitting machines having groups of inserted parallel walls of different thickness, the walls of each group having parallel opposed faces forming grooves for a plurality of needles, the leading and last walls of the group being of lesser thickness than an intermediate wall.

15. A dial having groups of inserted parallel walls of different thickness, the walls of each group having parallel opposed faces forming grooves for a plurality of needles, the leading wall being the thinnest of the group and the last wall being thinner than an intermediate wall.

In testimony whereof I have signed my name to this specification.

HARRY SWINGLEHURST.
